(57) **CLAIM**

The ornamental design for a display screen or portion thereof with graphical user interface, as shown and described.

DESCRIPTION

FIG. 1 is a first image of a display screen or portion thereof with graphical user interface in accordance with the present invention;

FIG. 2 is a second image of a display screen or portion thereof with graphical user interface in accordance with the present invention;

FIG. 3 is a third image of a display screen or portion thereof with graphical user interface in accordance with the present invention;

FIG. 4 is a fourth image of a display screen or portion thereof with graphical user interface in accordance with the present invention; and,

FIG. 5 is a fifth image of a display screen or portion thereof with graphical user interface in accordance with the present invention.

The broken lines showing a display screen or portion thereof form no part of the claimed design. The remaining broken lines that show portions of the graphical user interface are for illustrative purposes only and form no part of the claimed design.

The appearance of the display screen or portion thereof with graphical user interface sequentially transitions in a first embodiment of a sequence between the images shown in FIG. 1 to FIG. 2 to FIG. 3; and in a second embodiment of a sequence between the images shown in FIG. 1 to FIG. 2 to FIG. 4 to FIG. 5. The process or period in which one image transitions to another forms no part of the claimed design.
